UNITED STATES PATENT OFFICE.

JULIUS C. LE HARDY, OF SAVANNAH, GEORGIA.

HERNIAL TRUSS.

SPECIFICATION forming part of Letters Patent No. 699,095, dated April 29, 1902.

Application filed February 7, 1901. Serial No. 46,421. (No model.)

To all whom it may concern:

Be it known that I, JULIUS C. LE HARDY, a citizen of the United States, residing at Savannah, in the county of Chatham and State 5 of Georgia, have invented new and useful Improvements in Hernial Trusses, of which the following is a specification.

This invention relates to new and useful improvements in hernial trusses adapted for 10 use in the treatment of abdominal hernia. Its primary object is to furnish a hernial truss of simple and durable construction, of convenient application, and adaptable to all sizes of persons and all forms of abdominal hernia.

15 Another object is to so shape the wire as to permit the back or supporting pads to be placed in the hollow of the ileum above and back of the great trochanter, where they will not be affected by the movements of the body.

20 A further object is to provide pads adapted to all the different forms of hernia, and which can be readily adjusted and locked at any desired point along the wire of the truss; also, to provide hernial pads of oval form 25 swinging on a pivot to any desired angle of inclination.

Hernial pads in trusses heretofore employed have been held in position in one of three ways—*i. e.*, by a spring, an elastic band, or 30 by straps tightened upon the body. Although the pressure exerted upon the hernial pad by a spring or by an elastic band feels as though it were constantly increasing, it is under no control and can be overcome by straining or 35 any sudden motion of the body, such as that occasioned by coughing, sneezing, &c. If held in place by rigid straps, any strong muscular action or sudden change in the position of the body may alter the pressure on the pad 40 and let the intestines become displaced.

45 My invention consists in providing a truss where one or two metallic wires of proper size and stiffness may be used, the same being held securely in position upon the body by pads, which also serve to hold said wires or wire out of contact with the flesh. These wires are fitted to the body directly over the spot where the hernial pads are to be placed and may be adjusted for use in umbilical, 50 ventral, right and left femoral, or inguinal hernia, or any two or three of these.

The invention also consists in so shaping

the wire as to permit the same to extend across the abdomen, over the hips, and thence to points just above and back of the great 55 trochanter, in the hollow of the ileum, where its ends are securely held by pads. These pads are connected and held immovably in position by a strap passing across the back from one hip-pad to the other. By locating 60 the hip-pads at this point they are not interfered with by any motion of the body, and the hernial pad is therefore kept immovable in its position not by springs or straps, but by the resistance of the wire, which is also 65 immovable, the same being securely bound between the hip and hernial pads.

The invention also consists in so arranging the pads and shaping the wire that said wire will be held out of contact with the body at 70 all times.

I am aware that trusses have been devised which employ pads arranged upon a wire extending across the abdomen and hips; but in these the wire acts as a spring upon the hernial pad, angular bends being made along the wire at each side of the abdomen. The pressure is not, therefore, a direct pressure. The supporting-pads also have been arranged 75 at points upon the back, where they are subject to movement by muscular action and by motions of the body. In my improved truss the hernial pad is held securely in position in spite of any sudden strain or muscular action 80 of the body.

In the accompanying drawings I have illustrated my invention and the manner of using the same.

In said drawings, Figure 1 is a detail view of the hernial truss with the strap removed. 90 Fig. 2 is a top plan view of an oval hernial pad used in connection with this truss. Fig. 3 is a section therethrough. Fig. 4 is a top plan view of one of the hip-pads of the truss. Fig. 5 is a section therethrough. Fig. 6 is a 95 section through a pad especially adapted for use in treatment of femoral or ventral hernia. Fig. 7 is a similar view of a modified form of pad employed for umbilical hernia. Fig. 8 is a detail view of a modified form of sleeve for 100 the hip-pads. Fig. 9 illustrates the positions of the pads and wire in different forms of hernia. Fig. 10 is a side view showing the truss in position upon the body for the treatment

of left inguinal and umbilical hernia at the same time by employing two wires. Fig. 11 is a view of the back of the body and showing the hip-pads in position above and back of the great trochanter.

Referring to the figures by numerals and letters of reference, 1 is a curved wire which is adapted to extend across the abdomen and over the hernia. As shown in the drawings, 10 this wire is curved upward from the front central position in opposite directions, as shown at 2, and thence downward at the ends 3. Slidably mounted on the truss-wire 1 are binding-posts 4, having transverse apertures 15 a, through which the truss-wire is projected. Binding-screws 5 are let through the heads of the binding-posts and bear with their inner or lower ends on the wire, whereby the binding-posts, with the pads, may be clamped 20 to the wire at any required point. The binding-posts intermediate the hip-pads are formed at their inner ends with central studs 6, on which is loosely mounted a plate or disk 7, secured over a recess 8, formed in the outer 25 face of the hernial pad 9. A washer 10 is secured to the projecting end of the binding-post behind the plate 7 to hold the parts together. The hernial pad being thus pivotally supported can be readily placed in the 30 required direction to aline with the wound to be closed.

The studs 11 of the back-pads 12 are threaded and screwed into plates which are fastened to the supporting-pads 12. These pads are 35 circular in form and are arranged adjacent to the ends of the wire.

The hernial pad 9 is preferably oval, as shown, and can, as is obvious, be swung to any desired position upon its pivot to suit 40 inguinal and ventral hernia on the right or left side.

A strap 13 is detachably secured to the pads 12 and is adapted to extend across the back and prevent displacement of said pads. By 45 bending the wire 1 up or down the hernial pads may be adjusted for use in the various forms of hernia.

When the truss is applied, the pads 12 are adjusted so as to lie just above and back of 50 the great trochanter and in the hollow of the ileum, and the wire 1 will then curve over the hips and across the hernia. The strap 13 is placed in position and holds the pads 12 immovable, and as these pads are not affected 55 by any muscular action the position of the pad 9 will remain unchanged in spite of all strains and movements of the body. As the pads 9 and 12 are arranged between the wire 1 and the body, said wire will be held out of 60 contact with the body at all times. The pads may be made of hard rubber, wood, metal, porcelain, &c., and do not require soft coverings, as their pressure may be so regulated as to cause no chafing, pain, or inconven- 65 ience.

In Fig. 9 I have indicated by dotted lines the position of the pads in the various forms of hernia. In this figure, A is the position of the pad for umbilical hernia, B for one form of ventral hernia, C for right and left inguinal hernia, and D for right and left femoral hernia.

It is to be understood that the wire 1 does not at any time act as a spring, but passes directly over the hernial pad and connects 70 with the immovable pads 12, thereby holding said pad against displacement. Again, it must be understood that in my invention two or more wires may be used on the same truss for the relief of umbilical or high ventral 75 and of inguinal or femoral hernia at the same time. (See Fig. 10.) The wires are held by the same hip-pads, only that in this truss two circular openings are made for the wires in the binding-post of the pad, as shown in Fig. 80 3. Each wire is held secure in position by a set-screw 5 and acts separately and directly upon the hernial pads, holding each separately in its proper position.

Having thus described my invention, what 85 I claim, and desire to secure by Letters Patent, is—

1. A hernial truss comprising two wires bent to conform to the contour of different parts of the body and to stand free from the 90 surface thereof, binding-posts having duplicate wire-apertures to receive and hold the respective ends of the two wires, hip-pads secured to the said binding-posts, binding-posts adjustably mounted on each wire at the front 95 and intermediate the hip-pads, a hernial pad revolvably secured to the inner end of each intermediate binding-post, and a fastening-strap to unite the binding-posts of the hip-pads.

2. A hernial truss comprising a wire bent to the contour of the abdomen and hips and to stand free and away from the body with its ends terminating at points above and back of the great trochanter in the hollow 100 of the ileum, a plurality of binding-posts each having an aperture to adjustably engage over the wire at each end and a threaded stud at the inner end, a clamping-screw let through the head of each binding-post, a hip-pad 105 detachably secured to the threaded stud of each binding-post, a binding-post slidably mounted on the wire intermediate the hip-pads, a screw to clamp the binding-post to the wire, a plate revolvably secured to the inner end of 110 the binding-post, a hernial pad secured to the plate, and a fastening-strap connecting the binding-posts of the hip-pads.

In testimony whereof I affix my signature in presence of two witnesses.

JULIUS C. LE HARDY.
